H. C. Harrison.

UNITED STATES PATENT OFFICE.

JOHN ELLIS, OF ALLEGHENY, PENNSYLVANIA.

AUTOMATIC VALVE-OPERATING MECHANISM.

No. 862,147.

Specification of Letters Patent.

Patented Aug. 6, 1907.

Application filed May 2, 1906. Serial No. 314,770.

To all whom it may concern:

Be it known that I, JOHN ELLIS, a citizen of the United States, residing at Allegheny, in the county of Allegheny and State of Pennsylvania, have invented 5 certain new and useful Improvements in Automatic Valve-Operating-Mechanism; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to an improved automatic valve operating mechanism, and it is particularly adapted for 15 use in the opening and closing of seat-valves by the action of variable temperatures, variable pressure, the rise and fall of floats, or such other intermittent mechanism wherein it is necessary that said valve should open or close to regulate and control the quantity of 20 gas, water or other fluid delivered through the medium of said valve, and with these ends in view, the invention comprises a moving or sliding member, actuated by certain moving parts governed by varying temperature, pressure, &c., which when carried beyond a 25 dead-line or center, operates a spring actuated lever to either open or close the valve, as necessary, and the invention further consists in a means of adjustment regulative to the time or period of movement of said valve due to said variable conditions, and the invention 30 also consists in the certain details of construction and combination of parts, as will be fully described hereinafter.

In the accompanying drawings—Figure 1 is a side elevation of my improved automatic valve operating mechanism shown in connection with a thermostat regulator for water heaters, in which the valve is opened and closed for the purpose of regulating the supply of gas to the heater. Fig. 2 is an inverted plan view of the same. Fig. 3 is a front elevation of the regulator 35 and valve operating mechanism. Fig. 4 is an enlarged detailed side elevation of my improved device shown in connection with a portion of the valve stem. Fig. 5 is a front sectional elevation of the same. Fig. 6 is a side elevation of a modified form of my improved valve 40 operating mechanism, showing the same adapted for use in connection with a float.

For the purpose of illustrating the advantages and working of my improved device, I have shown at Figs. 1, 2 and 3 of the drawings, a thermostat gas regulator, 45 to regulate and control the flow of gas to a heater adapted to keep the water in a boiler at approximately even temperature. This regulator consists of a suitably formed shell 3 attached to the boiler 1 by means of a

threaded nipple 2, said shell having a gas inlet and outlet ports and intervening valve seat 5, upon which 55 a valve 6 is made to operate.

Arranged within the boiler 1, is a copper tube 4 with inclosed porcelain rod 25, the one expanding and contracting under the varying temperatures of the water in the boiler and the other practically inert. This 60 porcelain rod 25 projects through the shell 3 and is in contact with a pivoted (26,) lever 23, which contacts by an adjusting screw 24 with another lever 21, fulcrumed (22,) to a frame 4 formed integral with the shell 3, which lever extends over and beyond the stem 7 of 65 the valve 6, and the free end provided with a spring 20 fixed to a bracket 19, for the purpose of holding said lever to keep the porcelain rod 25 normally against the inner or closed end of the copper tube 4.

The free end of the valve stem 7 is fitted with adjustable nuts 8 and 9, and adjacent to said stem is a moving member 11 loosely connected (18,) to the main lever 21, said member being capable of a limited movement in slides 10, forming a part of a bracket rigidly attached to the shell 3. This 70 slide member 11 is provided with a bridge 12, having outwardly projecting pins 14, which form pivotal connections for two spiral springs 13, which occupy position at either side of said member, and the other extremities of said springs connected with similar pins 15, forming 75 a part of a bifurcated bar or lever 16, which bifurcation incloses the valve stem 7 at a point between the adjustable nuts 8 and 9. The other end of the bifurcated lever 16 is fulcrumed in a notch 17 formed in the bracket 10 at a point opposite to and midway between the center of the throw of the valve stem 7, in such manner that when the points of connection 14 of the springs 13 are over the dead-line or center the valve 6 will be pressed and held to its seat 5 or lifted 80 free from the same by the action of the springs 13. 90

In the operation of the above described regulator, the water in the boiler 1, having reached a certain predetermined temperature, and the device adjusted by means of the screw 24 to respond to that degree of heat, the copper tube 4 has expanded in the direction of its length permitting the rod 25 to recede, which motion is transmitted to the sliding member 11 through the medium of the compound levers 21 and 23. This movement of the lever 21 will carry the member 11 95 inward, moving the connections 14 beyond the dead line or point 17, causing the springs 13 to actuate the bar 16, to move in quick contact with the adjustable stop 18, the said springs 13 placing a pressure upon the same to move and hold the valve to its seat 5, to cut off the supply of gas to the heater. The supply 100 of gas being stopped or cut off from the heater, the

high temperature of the water in the boiler 1 will be gradually reduced and the tube 4 contracting will bring the parts back to their normal position to again supply the heater with gas, as is obvious.

5 At Fig. 6 of the drawings I have shown in connection with a float 31, a modified form of my invention, in which the pivoted lever 30 of said float operates the sliding member 11' by being brought in contact with stops 29, either adjustably attached or formed 10 integral with said member. In this modified form the valve stem 7' is fitted with adjustable nuts 9' and 8' similar to those above described, and the springs 13' and bifurcated lever 16, arranged at the front and in line with the sliding member 11. It will be readily 15 seen that the rise and fall of the float 31 will bring the pivoted connections 14' and 15' over the dead line or center of the lever 13', thereby opening and closing the valve.

This valve operating mechanism may be used for 20 a number of other purposes, and various slight alterations and changes may be made in the details of construction without departing from the spirit of the invention. Therefore I do not wish to confine myself to those shown and described, but wish to claim all

such modified forms, as would come properly within 25 the general scope of the invention.

Having thus described my invention, what I claim and desire to secure by Letters Patent, is:—

1. A mechanism for operating valves, comprising a primary actuating means connected to and operating a slide- 30 able member, a bar fulcrumed at a point midway of the movement of said member and suitable springs connecting the free end of the bar to the sliding member, whereby movement is imparted to the outer end of the bar when carried beyond the dead point or line by said sliding member, to open or close a valve, as described. 35

2. A valve operating mechanism comprising a slide- 40 able member connected to and operated by a primary actuating means, in combination with a valve stem having adjustable stops, a bifurcated bar or lever arranged within reach of said stops and fulcrumed midway of the movement of said sliding member, suitable springs connecting the free end of the bar with the sliding member at points normally out of line with the fulcrum of said bar, said springs acting to give movement to the bar when beyond the dead 45 point, as described.

In testimony whereof, I affix my signature, in presence of two witnesses.

JOHN ELLIS.
